HAMMER AND METHOD OF FABRICATING
SAMEMarvin M. Martin, South Gate, Calif., assignor to
Martool, Inc., South Gate, Calif., a corporation
of California

Application April 6, 1951, Serial No. 219,603

8 Claims. (Cl. 145—36)

1

This invention relates to hammers with special reference to hammers having relatively soft heads of lead, plastic materials and the like, and is directed to the problem of mounting such a molded head on a handle in such manner that the head and handle are effectively united for a long service life.

In the normal usage of such a hammer, the impacts of the head against work material and the centrifugal force engendered by swinging the hammer create excessive strains that tend to weaken the hammer structure to the point of separating the head from the handle. Various suggestions have been advanced heretofore for providing a permanent safe joint between the head and handle of such a hammer, but usually such constructions either are inadequate for meeting the strains of actual service or from the manufacturing view point are impractical.

The present invention achieves the required structural strength by providing what may be called a hammer frame in which a head sleeve and a handle are structurally interlocked by positive mutual engagement and in which a head or head body is cast in such manner as to additionally interlock the sleeve and handle.

Economy is achieved by using standard hollow stock material such as metal pipe or tubing for both the head sleeve and the handle and further economy is afforded by employing a rapid method of manufacture requiring relatively few and relatively simple fabrication steps.

To carry out this concept, a head sleeve cut from relatively large diameter tubular stock is bored from one side to receive the end portion of a handle cut from tubular stock of smaller diameter and a suitable procedure is carried out to unite the head sleeve and handle, thus to complete the hammer frame. In the preferred practice of the invention the handle is attached to the head sleeve in a positive manner both by welding and by mechanical interlocking engagement. The mutual interlocking engagement is accomplished simply by expanding the end portion of the handle after the end portion is inserted into the head sleeve.

The head or head body of lead, plastic, or other suitable material is then molded or cast to occupy the head sleeve, and imbedded engagement of the handle with the sleeve-embraced molded head further interlocks the head and handle. Thus, a structurally efficient hammer is produced in a simple inexpensive manner from stock materials and the rugged hammer frame may be used indefinitely by discarding worn

2

heads and molding new heads into the hammer frame as often as necessary.

It has been found that heads of widely different shapes are demanded in industry not only because the hammers are used for various purposes, but also because opinions differ as to the best shape of hammer head for a given purpose. Ordinarily it would be necessary to manufacture and stock many different models of the hammer to meet the diversified demand. A feature of the invention, however, is that the final step of casting or molding the head is a relatively simple procedure that may be carried out by the industrial purchaser. In practice, therefore, it is necessary to stock only the hammer frame comprising the interlocked head sleeve and handle, which hammer frame is sold as an article of manufacture for completion by the purchaser.

The various features and advantages of the invention may be understood from the accompanying drawings taken with the following detailed description.

In the drawings, which are to be regarded as merely illustrative,

25 Figure 1 is a side elevation of the presently preferred embodiment of the invention with portions shown in section;

Figure 2 is a top or plan view of the hammer frame;

30 Figure 3 is a section through the hammer head taken as indicated by the line 3—3 of Figure 1;

Figure 4 is a perspective view of an end portion of the handle prepared for insertion into the head sleeve; and

35 Figure 5 is a similar view of the end portion as expanded after insertion.

The principal parts of the preferred form of the invention shown in the drawings are a molded or cast head in the form of a body 10 carried by a hammer frame, generally designated 11, which hammer frame comprises a cylindrical head sleeve 12 and a handle 13. An end portion of the handle 13 extends into the interior of the head sleeve 12 and this end portion inside the head sleeve is suitably deformed or expanded for mechanical or structural interlock with the head sleeve. The handle 13 is not only interlocked directly with the head sleeve in this manner, but is also interlocked indirectly with the head sleeve by means of the head 10, since the handle is embedded in the head and the head in turn is embraced by the sleeve 12.

The structural relationships involved may be appreciated from a description of the preferred fabrication procedure. First, the head sleeve 12

is cut to length from suitable tubular stock and then is bored to provide a peripheral opening 16 to receive the end portion of the handle 13. In the preferred practice of the invention it is contemplated that the inserted end of the handle 13 will be welded to the wall of the head sleeve 12 opposite from the peripheral opening 16, and such welding may be facilitated by boring a second peripheral opening 17 in the head sleeve 12 diametrically opposite from the first mentioned peripheral opening 16.

The smaller diameter tubing for the handle 13 is cut to length and preferably is partially flattened along a portion of its length to provide a narrowed grip portion 20. It is also desirable to add an end fitting in the form of a metal plug 21. This end fitting 21 is formed with a shank 22 dimensioned to fit into the end of the handle 13 and is formed with a shoulder 23 to abut the handle end. The metal fitting 21 is also formed with a radial end flange 24 so that when the end fitting is united with the handle 13 by welding 25 the radial end flange 24 forms an enlargement on the outer end of the handle 13 that acts as a safeguard to keep the hammer from slipping from a workman's hand. If such a metal fitting 21 is added, it is desirable to bore a small hole 26 in the handle 13 to serve as a vent in the subsequent molding or casting of the head body 10.

In preparation for inserting the handle 13 into the head sleeve 12, at least one slit or slot, preferably longitudinal, is cut in the end portion. Thus, as shown in Figure 4, two slots 27 positioned diametrically apart are cut in the end portion of the handle 13. The slots 27 may, for example, be cut $\frac{1}{8}$ inch wide and, if desired, a $\frac{3}{8}$ inch hole 28 may be bored in the opposite walls of the handle at the location of the two slots 27 prior to the actual cutting of the slots.

The end portion of the handle 13 is then inserted into the interior of the head sleeve 12 through the peripheral opening 16 and, if the second peripheral opening 17 is provided, the leading end of the handle is extended through the second opening 17 or at least brought flush with the outer rim of the second opening so that the end of the handle may be welded to the head sleeve with the welding operation performed from the exterior of the head sleeve. After this welding operation the protruding portion of the handle 13 at the weld as well as any protruding welding may be ground away to conform smoothly with the cylindrical configuration of the head sleeve. The finished welding is indicated at 30 in Figure 1.

The next step is to expand or open up the two slots 27 of the handle 13 to deform the portion of the handle disposed within the head sleeve 12. This operation may be conveniently and effectively performed simply by driving a suitable swaging tool into the slots 27. Any suitable swaging tool may be used for this purpose, but one having a suitably dimensioned guide pin is preferred for the bore 28 formed at the medial portion of each of the slots 27 coacts with such a pin to locate and guide the tool into the desired engagement with the defining edges of the slots. In this expanding operation the swaging tool may be driven through both slots 27 in one operation to deform the handle as shown in Figure 5. This swaging action, in locally expanding the handle, tends to shorten the handle and consequently causes the same to creep further into

the head sleeve 12 and the handle is free to creep in the opening 16 to the needed degree.

It will be seen, referring now to Figure 3, that the cross-sectional dimensions of the portion of the handle after the swaging action have been increased, so that the end portion of the handle is larger than the opening 16 through which it has been inserted. Thus, while the welding 30 directly connects the handle 13 to the head sleeve 12, sole reliance is not placed on the welding inasmuch as the expanded end portion of the handle 13 is too large for retraction through the opening 16 in the head sleeve 12. Thus, even though the welding should fail the head sleeve can not become separated from the handle.

The tool in this stage of completion can be sold as an article of commerce for the final operation in the fabrication procedure of the hammer may be carried out by the purchaser. This article, which consists of the head sleeve 12 with the handle 13 now securely fixed to the same, is shown in Figure 2.

To complete the hammer, the purchaser merely molds or casts the head body 10 in such a manner that the head body occupies the interior of the head sleeve 12 and extends beyond the two end openings of the head sleeve. This operation requires merely a conventional mold having a cavity of the desired size and shape and it is not believed necessary to describe this molding operation, for it will be readily apparent to one skilled in the art.

Whether the molding operation is carried out by the fabricator of the head sleeve and handle or by the purchaser, the described construction for the hammer frame 11 permits the material of the head body 10, during the molding operation, to extend or flow into the interior of the handle 13 through the slots 27 and the body material may be permitted to extend into the shank of the handle 13 to any extent desired.

A feature of the invention is the numerous respects in which the head or head body 10 is engaged by the hammer frame 11. There is inter-engagement between the head and the hammer frame in that the material of the head extends into the shank of the handle, as indicated at 32 in Figure 1, and again in the fact that the material of the hammer head engages the rim of the peripheral opening 17 of the head sleeve as indicated at 33. There is further inter-engagement by virtue of the fact that the head 10 may be cast slightly oversize with respect to the inner diameter of the head sleeve 12 so that the head is formed with an annular shoulder 35 abutting against each end of the head sleeve 12, as shown in Figure 1.

As best shown in Figure 3, there is further inter-engagement between the head and the hammer frame in the way the expanded end portion of the handle 13 is imbedded in the material of the head. Thus, it will be noted in Figure 3 that the maximum cross-dimension of the material of the head inside the diameter of the handle 13 is greater than the entrances into the interior of the handle through the expanded slots 27 so that the material of the head is, in effect, trapped by the walls of the handle 13. It may also be noted in Figure 3 that the angular relation of the split walls of the handle 13, relative to the surrounding circumferential wall of the sleeve 12, entraps or mobilizes the material of the head 10 inside the sleeve.

A feature of the invention is that the sleeve

12, which surrounds the head 10, is prevented from separating from the handle 13, first, by the previously mentioned welding 30, second, by the previously mentioned expansion or enlargement of the end portion of the handle inside the sleeve, and, third, by the fact that the material of the head 10 serves as an agent to mechanically interlock the sleeve 12 with the handle 13. Thus, the fact that the expanded end portion of the handle 13 is embedded in the material of the head together with the fact that the head is embraced by the sleeve 12 in effect interlocks the sleeve and handle.

Although the now preferred embodiment of the present invention has been shown and described herein, it is to be understood that the invention is not to be limited thereto, for it is susceptible to changes in form and detail within the scope of the appended claims.

I claim:

1. A hammer of the character described comprising: a cylindrical head sleeve of rigid material having a peripheral opening; a handle having a hollow end portion projecting through said opening into said sleeve to extend transversely thereof; and a head casting occupying said sleeve and extending beyond at least one open end of the sleeve, the wall of the hollow end portion of said handle having at least one lateral opening through which the material of the head casting extends into said hollow portion of the handle, whereby the head casting rigidly interlocks the head sleeve and handle.

2. A hammer as set forth in claim 1 in which the cross-section of the material of the head casting inside said end portion of the handle is greater than the dimension of the opening whereby the head casting is interlocked with the handle.

3. A hammer of the character described, comprising: a cylindrical head sleeve of rigid material having a circular opening formed in the wall thereof; a tubular handle of circular cross-section having an end portion extending through said sleeve into the interior of the same; means bonding the end of said handle to the sleeve opposite said opening; and a head casting occupying said sleeve and extending beyond at least one open end of the sleeve, the wall of said end portion of the handle having a flared opening to form at least one passage through which the material of the casting extends for interlocking the head sleeve and casting, the flared opening providing a deformed end portion of the handle larger in cross-section than the opening of said sleeve.

4. A method of fabricating a hammer of the type described characterized by the use of hollow elongated stock material of two different cross-sectional sizes, said method including the steps of: cutting a head sleeve from the larger stock; cutting an opening in the periphery of the head sleeve slightly larger than the cross-sectional dimension of said smaller stock; cutting a piece of said smaller stock to size to serve as a handle; cutting at least one longitudinal slot in an end portion of said handle; inserting said end portion into said head sleeve through said opening; welding the end of said handle to the wall of said head sleeve opposite said opening; widening said slot while said end portion is inside said head sleeve to expand said end portion; and casting a head to occupy the interior of said head sleeve and to extend into said handle through said slot to interlock the handle and sleeve.

5. As an article of manufacture, a hammer frame adapted for the casting of a head integral

therewith, said frame comprising: a head sleeve of rigid material to embrace a central portion of said head, said sleeve having a centrally located peripheral opening therein; a hollow cylindrical handle having an end portion projecting into said sleeve through said opening and extending transversely of said sleeve, the end portion of said handle disposed within said sleeve being deformed to a cross-sectional dimension greater than the opening to hold said handle against separation from said sleeve; said end portion having an opening formed in the wall thereof whereby the interior of said sleeve communicates with the interior of said handle to form a flow passage for the material of the head during the casting of the same.

6. As an article of manufacture, a hammer frame adapted for the casting of a head unitary therewith, said frame comprising: a head sleeve of rigid material to embrace a central portion of said head, said sleeve having a pair of diametrically opposed peripheral openings therein; a hollow cylindrical handle having an end portion extending radially into said sleeve through one of said openings with the terminal of said end portion fitting within the other of said opening; and means bonding the terminal of said end portion to the material of said sleeve contiguous to the defining edges of said other opening to join said handle to said sleeve, the end portion of said handle disposed within said sleeve being deformed to a cross sectional dimension greater than the openings to augment the jointure effected by said bonding means and to interlockingly hold said handle against separation from said sleeve and to form an anchoring means to be embedded within and interlockingly engaged with the material of the head as the same is cast.

7. A hammer of the type described, comprising: a head sleeve of rigid material, said sleeve having a pair of diametrically opposed peripheral openings therein; a hollow cylindrical handle having an end portion projecting into said sleeve through one of said openings and diametrically extending across said sleeve; means bonding the terminal portion of said handle to the material of said sleeve contiguous to the defining edges of said other opening, the end portion of said handle disposed within said sleeve having an opening therethrough, the defining edges of which are deformed to a cross-sectional dimension greater than the openings of said sleeve; and a head casting completely filling said sleeve and integrally extending through the opening of said handle to occupy at least the portion thereof disposed within said sleeve to rigidly interlock the head with the sleeve and handle.

8. A method of fabricating a hammer frame of the type described characterized by the use of hollow elongated stock material of two different cross-sectional sizes, said method including the steps of: cutting a head sleeve from the larger stock; cutting an opening in the periphery of the head sleeve slightly larger than the cross-sectional dimension of said smaller stock; cutting a piece of said smaller stock to size to serve as a handle; cutting at least one longitudinal slot in an end portion of said handle; inserting said end portion into said head sleeve through said opening to dispose the slot for access through one open end thereof; welding the end of said handle to the wall of said head sleeve opposite said opening; and thereafter inserting a tool through said open end and swaging outwardly the defining edges of said slot to expand said end portion of

the handle into a division larger in cross-section than the opening of said head sleeve to augment the jointure of the weld and to form an anchoring means adapted to be embedded within and interlockingly engaged with the material of a head subsequently cast about said head sleeve and filling the same.
